UNITED STATES PATENT OFFICE.

WILLIAM GRIMSHAW, OF GLENELLYN, ILLINOIS.

FIRE-EXTINGUISHER.

1,268,454.

Specification of Letters Patent.

Patented June 4, 1918.

Application filed November 20, 1917. Serial No. 202,912.

To all whom it may concern:

Be it known that I, WILLIAM GRIMSHAW, a citizen of the United States, and a resident of Glenellyn, in the county of Dupage and State of Illinois, have invented a new and useful Fire-Extinguisher, of which the following is a specification.

This invention relates to fire extinguishers and relates particularly to fusible members 10 designed and adapted for use in automatic sprinklers and the like.

The object of the invention is to provide a fusible member for this purpose which shall combine the features of simplicity and 15 relative cheapness of construction, requisite strength and reliability and uniformity of operation in use. To this end, a fusible member of my invention comprises the various features, combinations of features and 20 details of construction hereinafter described and claimed.

In the accompanying drawings, in which my invention is fully illustrated,

Figure 1 is a side view, several times enlarged, of a fusible member of my invention.

Fig. 2 is a top plan view thereof.

Fig. 3 is a bottom plan view thereof.

Fig. 4 is an end view thereof from the position 4—4 of Fig. 1.

Figs. 5 and 6 are sectional views thereof on the lines 5—5 and 6—6 of Fig. 1.

Figs. 7 and 8 are views substantially similar to Figs. 1 and 3, respectively, illustrating a modification of my improved fusible member.

Fig. 9 is a sectional view on the line 9—9 of Fig. 7.

Fig. 10 is a side view substantially similar 40 to Fig. 1, illustrating still another modification of my improved fusible member.

Fig. 11 is an end view thereof from the position 11—11 of Fig. 10; and

Fig. 12 is a fragmentary sectional view 45 of the connected ends of the toggle arms, on the line 12—12 of Fig. 11.

My improved fusible member is what may be described as of the toggle type, comprising toggle members respectively designated, 50 as a whole, A, A¹, comprising strut portions 1 and 2, respectively, the remote ends of which are provided with bearings adapted to engage corresponding bearings on the parts of the sprinkler between which said strut members 1 and 2 are adapted to be in-

serted in use, to-wit, the cap 3 which closes the discharge nozzle of the sprinkler, shown at 4, and the adjusting screw 5 threaded through the boss 6. The adjacent ends of the strut portions of said toggle members 60 are articulated by means of a suitable joint consisting, as shown, of a V-edge 7 on the lower strut 1 which engages a corresponding V-groove formed in the upper strut 2, the angle of the V-groove being preferably 65 somewhat greater than the angle of the V-edge 7, thus providing for perfect freedom of movement between the articulated ends of said toggle levers.

Said toggle members also comprise toggle 70 arms designated 9 and 10, respectively, which project laterally from the struts 1 and 2 and which, in use, are connected by a member or members soldered to one or both thereof and which projects or project beyond the toggle 75 arm to which they are soldered and interlock with a rigid shoulder formed on the other of said toggle arms or the projecting ends of which interlock with each other.

Referring now to Figs. 1 to 6 of the drawings, in which I have shown what I now consider to be the preferable form of my invention, the toggle members A, A¹ are so constructed and connected that, when the tension screw 5 is tightened, the compression to which the struts 1 and 2 are subjected, will tend to flex said toggle members in a direction to separate the ends of the toggle arms 9 and 10, and the ends of the toggle arms 9 and 10 are connected by means 85 of a plate 11 soldered to the under side of the toggle arm 9. The end of said plate projects beyond the end of said toggle arm 9 and interlocks with a shoulder 12 formed at the end of the toggle arm 10 beyond the 90 end of the toggle arm, the extreme outer end of said toggle arm 10 extending downwardly to bring said shoulder 12 in proper position for engagement by the plate 11.

It is thus obvious that, in use, said plate 100 11 will form what may be described as a lever of the first class, the fulcrum being at the extreme end of the toggle arm 9, the power being applied at the shoulder 12, and the soldered joint representing the load. 105

In operation, it is obvious that so long as the soldered joint which secures the plate 11 to the toggle arm 9 remains intact, the toggle members will maintain the cap 3 in position to close the nozzle of the sprinkler. 110

As soon, however, as said soldered joint ruptures under the action of heat, the pressure to which the strut portions 1 and 2 are subjected will cause the toggle members A, 5 A' to collapse or fly apart, thus releasing the cap 3 and permitting the water to discharge through the nozzle of the sprinkler, in the manner contemplated.

- To prevent bending or springing of the 10 toggle arm 9 by the bending moment produced in said arm by the tension of the shoulder 12 acting on the end of the plate 11, I preferably reinforce or strengthen said toggle arm 9 by a rib 13, which extends outwardly toward the end of said toggle arm a sufficient distance beyond the inner end of the plate 11 to impart desired rigidity to said toggle arm to insure against springing or bending thereof.
- 15 To strengthen the solder joint which connects the plate 11 to the member 9 and also to prevent corrosion of said joint adjacent to the rib 13 by the action of chlorine, nitric acid and other fumes to which the sprinklers may 20 be subjected in use, said plate 11 is preferably stamped up, as shown at 14, to form a groove 15 on its inner side adapted to receive the rib 13, said groove being shaped to conform generally to the shape of said rib 25 and being sufficiently large to receive said rib without binding. By soldering the sides of said rib 13 and groove 15 together, the area of the solder surface connecting said plate 11 to said toggle member 9 will be very 30 materially increased and strengthened while, at the same time, corrosion of said solder joint adjacent to said rib will be effectually prevented, all in the manner described. It is 35 recognized that corrosion of the solder which connects said plate to said toggle arm, will harden said solder and raise its fusing point to such an extent as to prevent the designed 40 operation of the sprinkler, thus destroying the practical value of said sprinkler as a protection against fire.

As a modification of my invention, I contemplate a construction in which the outer ends of the toggle arms are connected by means of plates, substantially like the plate 50 11, the ends of which project beyond the ends of the toggle arms and are interlocked in any suitable manner so as to provide a rigid connection between the same.

This construction has an important advantage in the respect that the toggle members may be practical duplicates of each other excepting as regards the joint by which the strut portions of said toggle members are articulated.

60 This construction is shown in Figs. 7, 8, and 9 of the drawings, in which A² designates the lower toggle member, A³ the upper toggle member, 1¹ and 2¹ the strut portions and 9¹ and 10¹ the toggle arms of said members A² and A³, respectively, 11¹ the plate

soldered to the under side of the toggle arm 9¹, 11² the corresponding plate soldered to the toggle arm 10¹.

Said plates 11¹ and 11² are stamped up, as shown at 14¹ and 14², to form grooves 15¹ 70 and 15² adapted to receive the strengthening ribs 13¹ and 13² on the toggle arms, all substantially in the same manner as in the preferred form of link shown in Figs. 1 to 6.

The outer ends of said plates 11¹ and 11² 75 project beyond the ends of the toggle arms 9¹ and 10¹ and are bent inwardly toward each other and are provided with interlocking parts which will operate to rigidly connect the ends of said plates, thus affording the desired fusible connection between the toggle members A² and A³.

As shown, the end of the plate 11¹ engages a hook 16 formed by turning the extreme outer end of the plate 11² backwardly upon itself, leaving a sufficient space between the bent sections thereof to receive the end of the plate 11², said space being sufficiently wide to receive the end of the plate 11¹ loosely to permit said plates to turn pivotally to release the toggle members A² and A³ when the soldered joint connecting either or both of the plates 11¹ and 11² to the toggle arms to which they are connected, respectively, fuses.

As still a further modification of my improved fusible member, I contemplate connecting the projecting end of the plate 11 soldered to the toggle arm 9, to the end of the toggle arm 10 by means of a shouldered 100 lug formed on the toggle arm 10 which is provided with a shoulder adapted to engage or interlock with a hole formed in the end of the plate soldered to the toggle arm 9, the extreme ends of said plate and of said toggle 105 arm 10 being bent inwardly toward each other to bring the same into proper relation to effect engagement of said lug and hole.

This modification is shown in Figs. 10, 11 and 12 of the drawings, in which 9² and 10² 110 designate the toggle arms, 11³ the plate soldered to the toggle arm 9², 17 the lug formed on the toggle arm 10² formed on which is a shoulder 18 which interlocks with the side of a hole 19 formed through the projecting end 115 of the plate 11³, the ends of said plate 11³ and of said toggle arm 10² being turned inwardly toward each other to bring the projection 17 and the hole 19 in proper relative position so that said lug and hole will interlock.

I claim:

1. In a fusible member for the purpose specified, toggle members comprising articulated strut portions and arms thereon, a 125 plate soldered to one of said toggle arms, and connection between said plate and the other toggle arm, the toggle arm to which said plate is soldered having a rib on the side thereof to which said plate is soldered, and 130

said plate being shaped to form a groove to receive the portion of said rib which extends beneath it, substantially as described.

2. In a fusible member for the purpose specified, toggle members comprising articulated strut portions and arms thereon, a plate soldered to one of said toggle arms, and connection between said plate and the other toggle arm, the toggle arm to which said plate is soldered having a rib on the side thereof to which said plate is soldered, and said plate being shaped to form a groove to receive the portion of said rib which extends beneath it and the sides of said rib and groove being soldered together, substantially as described.
3. In a fusible member for the purpose specified, toggle members comprising articulated strut portions and arms thereon, plates soldered to said toggle arms, respectively, and connection between said plates, said toggle arms having ribs on the sides thereof to

which said plates are soldered, and said plates being shaped to form grooves to receive the portions of said ribs which they overlap, substantially as described. 25

4. In a fusible member for the purpose specified, toggle members comprising articulated strut portions and arms thereon, plates soldered to said toggle arms, respectively, and connection between said plates, said toggle arms having ribs on the sides thereof to which said plates are soldered, and said plates being shaped to form grooves to receive the portions of said ribs which they overlap, and the sides of said ribs and 35 grooves being soldered together, substantially as described.

In testimony, that I claim the foregoing as my invention, I affix my signature this 12th day of November, A. D. 1917.

WM. GRIMSHAW.
